UNITED STATES PATENT OFFICE

2,669,744

PNEUMATIC LINT COLLECTION APPARATUS
FOR TEXTILE MACHINES

Dennis B. Parrish, Clover, S. C.

Application November 19, 1951, Serial No. 257,075

2 Claims. (Cl. 15—301)

1

This invention relates to apparatus for collecting lint and foreign matter from textile machines and more especially to a lint collection apparatus for elongated textile machines, such as spinning machines and twisters.

One type of apparatus heretofore in use for preventing the accumulation of lint and other foreign matter on the drawing rolls of a twister or spinning frame has included a series of relatively small suction pipes of substantially the same diameter as the diameter of the drawing rolls of the machines. These relatively small suction pipes have been positioned adjacent the drawing rolls and have had perforations in the upper walls thereof which were disposed in close proximity to the lower surfaces of the drawing rolls. Suitable relatively small ducts extended from each of these relatively small horizontal pipes to a relatively large longitudinally extending suction pipe having an opening in one end thereof and being connected at its other end to a suitable housing. The housing contained a filter, such as a screen or the like and a suction fan disposed on the opposite sides of the filter from the suction pipe to thus create suction in the relatively large manifold or suction pipe and relatively small pipes to draw lint or foreign matter from the rolls through the pipes and to collect the lint upon the screen or filter.

The usual housing in which the screen and filter have heretofore been disposed has a discharge opening therein on the opposite side thereof from the suction pipe and a blast of air generated by the fan would be exhausted through this opening. In some instances, this air has been carried away through extensive ductworks, but generally it has been exhausted into the area adjacent the machine. Since the housing is usually disposed in about the same elevation as the head of a person walking past the same, the blast of air therefrom has been objectionable and workmen moving by the machine in a textile plant would have to dodge the hot blast of air in order to escape the same and to prevent lint and the like from being blown onto them.

Further, it should be noted that humidity is an important factor in the processing of textile fibers and most spinning and twisting machines are equipped with humidifiers for adding moisture to the air to increase the humidity thereof. The hot blast of air which is exhausted from the housing of cleaning apparatus of the type described tends to lower the humidity of the air around the textile machine to thus require increased use of humidifiers, as well as increasing

2

the difficulty of maintaining proper humidity. Frequently, the humidifiers are placed adjacent the housing for the cleaning apparatus and the hot blast of air from this housing more or less nullifies the effect of the humidifier.

It is, therefore, an object of this invention to provide means for utilizing the blast of exhaust air from the housing above described to further prevent accumulations of lint and other foreign matter on parts of the machine for better cleaning and to prevent the hot air from being exhausted into the aisle at one end of the machine. To this end, I have provided a duct having one end thereof communicating with the discharge opening in the housing, and a portion extending longitudinally of the machine near the lower portion of the machine and this duct being closed at its end remote from the housing and also being provided with a row of longitudinally spaced openings at the upper portion thereof to thus exhaust the exhaust air from the housing through these openings. This creates blasts of air upwardly past the various parts of the machine to maintain agitation of the lint and other foreign matter which would normally collect upon adjacent parts of the machine. Thus, a substantial part of the lint or foreign matter which would normally collect on the lower portion of the machine is directed upwardly and drawn into the conventional suction pipes disposed adjacent the drawing or drafting rolls of the machine to be collected on the screen in said housing. Lint and other foreign matter which does not settle on the drawing or drafting rolls or is not picked up by the conventional suction pipes would, nevertheless, remain in agitation with the result that this surplus foreign matter or lint would collect at points remote from the machine thereby greatly facilitating the operation of the machine and the periodic cleaning of the machine.

Some of the objects of the invention having been stated, other objects will appear as the description proceeds, when taken in connection with the accompanying drawings, in which—

Figure 1 is a fragmentary, somewhat schematic, elevation of a spinning frame, roving frame, twister or the like showing the improved lint agitating and collection apparatus mounted thereon;

Figure 2 is an elevation looking at the left-hand end of Figure 1 with the upper portion thereof broken away;

Figure 3 is a fragmentary, somewhat schematic, elevation of the textile machine looking

at the opposite side from that shown in Figure 1 with parts broken away;

Figure 4 is a sectional plan view taken substantially along the line 4-4 in Figure 3 and showing the textile machine somewhat schematically;

Figure 5 is a schematic vertical sectional view taken substantially along the line 5-5 in Figure 3;

Figure 6 is a fragmentary longitudinal vertical sectional view taken substantially along the line 6-6 in Figure 4 illustrating a portion of the improved compressed air discharge pipe.

Referring more specifically to the drawings, the numeral 10 broadly designates the frame of an elongated textile machine such as a spinning machine, twister machine, roving machine or the like and which frame comprises a head end frame member 11 and a foot end frame member 12 which is spaced substantially from the head end frame member 11. This type of machine usually has a plurality of Sampsons 13 disposed at spaced points longitudinally of the machine between head end 11 and foot end 12, only one of these Sampsons 13 being shown in the drawings. The head end 11, foot end 12 and Sampsons 13 usually support a horizontally disposed roll stand rail 14 and a horizontally disposed bolster or spindle rail 15. A vertically movable ring rail 16 is spaced above the spindle rail 15 and has a plurality of rings 16a thereon. The bolster or spindle rail 15 usually has a plurality of spindles 15a mounted thereon which are driven by means of endless tapes or cords 17 which extend inwardly and are guided by pulleys 18 so as to at least partially encircle a spindle driving cylinder 20 for driving the spindles 15a in the usual manner.

The cylinder 20 is mounted centrally of the machine and extends longitudinally thereof and is mounted on a drive shaft 21 which is rotatably mounted in the frame members 11 and 12 in a conventional manner and is driven continuously by any suitable means, such as V-pulleys 22 (Figure 2), which are engaged by V-belts 23. The V-belts 23 extend downwardly and are mounted on corresponding V-pulleys 24 which are fixed on a shaft 25 of an electric motor 26. The electric motor 26 has electric wires 27 and 28 extending therefrom to a suitable source of electrical energy, not shown.

The particular type of textile machine shown in Figures 1, 2, 3, 4 and 5 has a suitable creel stand, generally designated at 31, thereon which is disposed above and supported by the end frame members 11 and 12. The creel 31 carries a plurality of yarn filled bobbins or spools 32 from each of which a strand of yarn Y (Figure 5) is directed to a series of drawing or drafting rolls 34 which are shown schematically in Figures 1, 3 and 5. Of course, the yarns Y extend from the drawing rolls 34 downwardly to bobbins 35 which are supported on the spindles 15a.

Now, there is disposed in parallel relation to and adjacent the longitudinally extending groups of the drawing rolls 34 a plurality of longitudinally extending suction tubes or relatively small pipes 40, each of these pipes being provided with at least one longitudinally extending opening or slot 41 (Figure 5) in the upper portion thereof disposed in closely spaced relation to the lower surfaces of the adjacent drawing rolls 34. Each of the suction tubes or pipes 40 has a relatively small pipe 42 connected thereto for communication therewith and which, as shown in Figure 5,

extends inwardly towards the center of the machine and then downwardly and is connected to a relatively large longitudinally extending manifold pipe or duct broadly designated at 43 and which is shown as being rectangular in cross-section in Figures 2 and 5.

The manifold duct 43 has bottom and top walls 44 and 45 and side walls 46 and is closed at one end thereof, preferably the end adjacent the head end frame member 11, by an end wall 47. This end wall 47 is provided with an opening 50 therein to permit air to be drawn therethrough by means to be later described and this air will have the effect of an aspirator on the pipes 42 and 41, thus, creating a suction in the pipes 42 and 41. Whereupon the lint and other foreign matter which normally collects on the drawing rolls 34 will be sucked through the openings 41 in the suction tubes 40 and thus through the pipes 42 and 43.

Referring to Figure 1, it will be observed that the manifold duct 43 extends longitudinally of the machine below the horizontal plane of the rail 14 and through the foot end frame member 12, this foot end frame member 12 being provided with the usual opening 12a therethrough, through which the manifold duct 43 extends. The manifold duct 43 then curves upwardly and is connected to a collecting unit or suction unit housing 51 which is substantially cubical in shape and which has chambers 52 and 53 therein. The pipe or manifold duct 43 is connected to the bottom of the housing 51 for communication with the chamber 52. The chambers 52 and 53 are defined at their juncture by a suitable filter or screen 54, which is shown schematically in Figure 1.

The chamber 53 has suction means disposed therein such as a centrifugal fan 55. This fan 55 is fixed on a shaft 56 rotatably mounted in the corresponding wall of the housing 51 and which projects outwardly relative to the frame 10 and has a sprocket wheel 57 fixed thereon. The sprocket wheel 57 is engaged by an endless sprocket chain 60 which extends downwardly in Figures 1, 2 and 4 and engages a sprocket wheel 61 fixed on a shaft 62 extending from an electric motor 63. The housing 51 is supported on a platform 64 suitably secured to brackets 64a projecting from the foot end frame member 12 adjacent the upper end thereof. The platform 64 also supports the electric motor 63, which is suitably secured to the lower surface thereof, as by screws 65. The electric motor 63 has wires 66 and 67 extending therefrom to a suitable source of electrical energy, not shown.

It is thus seen that the exhaust or suction fan 55 creates a suction in the chamber 52 thereby causing the lint and other foreign matter that enters the manifold duct 43 to be drawn into the chamber 52 and against the screen or filter 54. This particular screen or filter 54 is of a type which may be easily removed from the housing 51 periodically in order to remove the accumulated lint therefrom.

The structure thus far described relating to the suction means is commonly referred to as a "Pneumafil attachment" and it is with this apparatus that the improved lint agitating and collecting means is adapted to be used.

It might be stated that, heretofore, the housing 51 has had an opening in the outer wall thereof relative to the frame 10 disposed adjacent the upper wall thereof and through which opening, the compressed air created by the fan

5 was exhausted. As is well known, the temperature and humidity in a textile plant is relatively high with the result that it was extremely uncomfortable for the operators or workmen in the textile plant to move past the discharge opening heretofore provided in the housing 51. Also, the compressed air created by the fan 55 was usually wasted and acted to decrease the humidity.

Now, in order to utilize the compressed air discharged from the chamber 53 of the housing 51 to provide additional cleaning means for the machine and prevent the humidity from being lowered by the exhaust air, I have relocated the exhaust opening in the chamber 53 of the housing 51 as shown at 53a in Figure 2 and have connected to the lower bottom wall of the chamber 53 a substantially rectangular branch duct 75, the upper end of which communicates with the opening 53a.

The branch duct or pipe 75 extends downwardly in Figures 1, 2 and 3 and inwardly and has a frusto-pyramidal pipe fitting 76 connected thereto for communication therewith. The end of the pipe fitting 76 remote from the branch duct 75 has one end of a lint agitating exhaust pipe 77 connected thereto for communication therewith and which extends longitudinally of the machine adjacent the lower portion thereof and which is supported by any suitable means such as strap members 80, only one of which is shown in Figures 3, 4 and 5. These strap members 80 partially surround the pipe 77, which is preferably circular in cross-section, and extend outwardly and are suitably secured to corresponding frame members, such as the Sampsons 13.

As heretofore stated, the pipe 77 extends longitudinally of the machine for substantially the entire length thereof and, it will be observed in Figure 6, that the end of the pipe 77 remote from the fitting 76 is closed, as at 81. The uppermost portion of the wall of the pipe 77 is provided with a longitudinally extending row of spaced openings or apertures 82.

Now, as the fan 55 rotates to create suction in the chamber 52, the manifold duct 43 and the pipes 42 and 40, the compressed air created by the fan 55 is discharged through the opening 53a (Figure 2). The compressed air then flows through the duct 75, the pipe fitting 76 and the pipe 77 to be exhausted through the apertures 82. These apertures 82 being relatively small, the compressed air will be emitted therefrom at a relatively high force as compared with the force of the compressed air passing through the duct 75, the pipe fitting 76 and into the pipe 77. Thus, an upward blast of air is emitted from each of the apertures 82 and these blasts of compressed air create a continuous turbulence in the air adjacent the various parts of the textile machine which are disposed above the pipe 77. This prevents any lint or other foreign matter from accumulating on any of the parts of the machine disposed above the pipe 77 and with the result that the lint and foreign matter will settle only at points remote from the machine while that portion of the lint and other foreign matter which is directed upwardly onto or adjacent the drawing rolls 34 will be sucked into the suction tubes 40 to finally become lodged against the right-hand surface of the screen or filter 54 in Figure 1 or against the surface of the screen or filter 54 disposed adjacent the chamber 52.

It is thus seen that I have provided an efficient system of utilizing the exhaust air from an air cleaner for a textile machine which comprises conducting the air downwardly from said cleaner and then longitudinally of the textile machine and then upwardly in a plurality of blasts to create a constant circulation of air about the parts of the machine for better cleaning thereof.

In the drawings and specification, there has been set forth a preferred embodiment of the invention and although specific terms are employed, they are used in a generic and descriptive sense only and not for purposes of limitation, the scope of the invention being defined in the claims.

I claim:

1. In a textile machine having an air cleaner comprising suction tubes disposed at the upper portion of said machine and connected to an open-end housing mounted on one end of said machine and having a suction fan and a filter therein, means for utilizing the exhaust air from said suction fan comprising means for closing the open end of said housing, a branch pipe communicatively connected to said housing and extending downwardly therefrom to the lower portion of said machine, a lint agitating exhaust pipe connected at one end to said branch pipe and extending longitudinally of the machine at the lower portion thereof and being closed at its other end, said lint agitating exhaust pipe having a plurality of longitudinally spaced openings in the upper portion thereof to permit said exhaust air to be emitted therefrom in a plurality of upwardly directed blasts for additionally cleaning the machine.

2. In a textile machine having an air cleaner comprising suction tubes disposed at the upper portion of said machine and connected to an open-end housing mounted at one end of said machine and having a suction fan and a filter therein, means for utilizing the exhaust air from said suction fan comprising means for closing the open end of said housing, a branch pipe connected to said housing and forming the only outlet for said housing, said branch pipe extending downwardly from said housing to the lower portion of said machine and then extending inwardly toward the end of said machine, a fitting connected to the lower end of said branch pipe, a lint agitating exhaust pipe having one end thereof connected to said fitting and extending longitudinally through the lower portion of the textile machine and having its other end closed, said lint agitating exhaust pipe having a plurality of longitudinally spaced openings in the upper portion thereof to permit exhaust air to escape therefrom in a plurality of upwardly directed blasts thus causing constant circulation of air about the parts of the machine disposed above said lint agitating exhaust pipe to clean the same.

DENNIS B. PARRISH.
